UNITED STATES PATENT OFFICE.

WILLIAM R. HOWDON, OF ANNISTON, ALABAMA.

AIR BRAKE.

Application filed April 22, 1927. Serial No. 185,829.

This invention relates to improvements in air brakes.

More particularly, the present invention relates to a sanding attachment for automatic railway air brake valves such as the 5 Westinghouse H. 6 brake valve or the like.

The prime purpose of the invention is to provide an attachment for brake valves of the type above characterized that will enable a sanding of rails previous to application of brakes.

It is also an important object of the invention that the attachment can be operated by the engineer's hand used for operating 10 the brake valve handle.

It is a further object of the invention that the attachment will in no way interfere with the operation of the brake valve to which the same may be applied.

20 Other objects, and objects relating to details of construction, combination and arrangements of parts will hereinafter appear in the detail description to follow.

The invention is illustrated by way of example in the accompanying drawings, in which:

Figure 1 is a top plan view of a brake valve with the present invention applied,

Figure 2 is a view in side elevation of the 30 same,

Figure 3 is a plan view of the rotary valve as modified for the purpose of the present invention,

Figure 4 is a similar view of the rotary 35 valve seat, and

Figure 5 is a fragmentary perspective view of a valve and operating handle therefor constituting in part the sanding attachment of the present invention.

40 Referring to the drawings more particularly in Figures 1 and 2, 10 indicates generally an automatic brake valve, of which 11 is the operating handle, 12 the casing for the rotary valve and 13 the rotary valve seat.

45 The operating handle, as is well known has six positions, namely, release, running, holding, lap, service, and emergency. These positions are indicated in Figures 1 and 4. In Figure 3, 10' indicates generally the rotary valve, and in Figure 4, 11' indicates generally the rotary valve seat.

50 It should here be noted that certain sanding operations are provided with the opera-

tion of the automatic air brake valves. The sand is serviced, however, after the brakes 55 are applied and certain beneficial results cannot be obtained as with an operation wherein the sanding of rails takes place previous to application of brakes as is the purpose of the present invention.

60 It should also be noted that the usual sanding appliances are used in conjunction with my invention. The present invention deals with the starting and stopping of sanding rails and only attachments and 65 changes in the regular automatic brake valve are necessary.

70 In applying my invention to a brake valve of the type shown in Figures 1 to 4 inclusive, there is provided a one way valve 14 preferably of the type shown in Figure 5. This valve is secured in any convenient manner to the valve 10 as shown in Figures 1 and 2. The one way valve is provided with an operating handle 15 which lies beneath the operating handle 11 of the automatic valve 10, when in released position. Stops 16 and 17 are provided for handle 15 to limit the movement thereof in both directions. When the handle 15 is in a vertical position and 75 against stop 17 the same is open. The valve is fully closed when the handle rests against stop 16.

80 In the valve 10' I provide an opening or passage 18, and in the valve seat 11' I provide a groove 19 which extends between running position and service position of the brake handle 11 as illustrated to advantage in Figure 4. I also provide a groove 20 for the emergency position of the operating lever 11. Only a short bridge 21 exists between the grooves 19 and 20', and the grooves preferably are located in the valve seat 11' as shown. The groove 19 communicates with a pipe 22 which is connected to one end of the one way valve 14. Groove 20 communicates with a passage 23 which in turn communicates with a pipe 24. Pipe 24 is connected with the remaining end of the one way valve 14 by pipe 25. Pipe 25 90 may be extended to the sanding apparatus, and supply air for operating the same in a manner to be hereinafter described.

95 As shown to advantage in Figure 1, when the brake valve handle 11 is in its released position the valve handle 15 is substantially 100 105

horizontally disposed and the one way valve controlled thereby is closed. The brake valve handle 11 operates to hold the handle 15 in its last named position as long as the 5 same is in its release position.

If the brake valve handle 11 is in running position and the engineer wishes to apply the brakes, and also wishes to sand the rails previous to the application of the brakes, 10 then with his hand upon the handle 11 he should lift the handle or lever 15 to an upright position and against the handle 11, and thus open the one way valve. With the one way valve open air will flow through 15 passage 18, groove 19, passage 22, valve 14, to pipe 25, and from thence to the sanders and operate the same in the usual manner. The air will continue to flow in the manner described for operating the rail sanding 20 apparatus until the operating handle passes its service position, after which the air will change its course and instead of passing through the valve 14 will pass through passage 23 and directly to the rail sanding apparatus.

When the operating handle 11 is returned to its release position the same will operate to bring the handle 15 to its horizontal position and close the one way valve 14.

30 From the foregoing it is apparent that the sanding of rails can be accomplished previous to the application of either service or emergency brakes in a positive and certain manner, and that such operation can be carried out without interference with the operation of the brake valve.

While I have shown and described the preferred application of my invention, to an automatic brake valve I am well aware that 40 changes might be made in such application by those skilled in the art without departing from the spirit of my invention.

I claim:

1. In combination with a brake valve of 45 the character described, means whereby a rail sanding operation may be accomplished previous to the application of brakes by said valve and only after the latter has been actuated from normally released position.

50 2. In combination with an automatic brake valve of the character described, a valve adapted to cause sanding of rails previous to application of brakes by said automatic valve, said second mentioned valve being operable only after said automatic brake valve has been actuated from normally released position.

55 3. In combination with an automatic brake valve having an operating handle, 60 means adapted to operate for causing a rail sanding operation previous to the brake application position of said handle, said means being operable only after said handle has been actuated to set said automatic brake 65 valve to running position.

4. In combination with an automatic brake valve having an operating handle which may be brought to a running and service brake positions, means operable in conjunction with said handle whereby a rail sanding operation may be carried out previous to the handle assuming its service brake positions, said means being rendered inoperative after said handle is moved past the service position of said automatic brake 75 valve.

5. In combination with an automatic brake valve having an operating handle which may be brought to running service brake and emergency brake positions means operable with the brake handle whereby a rail sanding operation may be caused previous to the handle assuming either of the brake positions, said means being rendered inoperative after said handle is moved past the 80 service position of said automatic brake valve.

6. In combination with an automatic brake valve having an operating handle, means operable with said handle adapted to operate for causing a rail sanding operation previous to the brake application position of said handle, said means being adapted to be rendered inoperative with the brake handle assuming its release position.

7. In combination with an automatic brake valve having a handle which may be brought to brake positions, a second handle adapted to be swung by the hand of an operator upon the automatic brake handle, and means associated with the second handle whereby with swinging the same to a certain position a rail sanding operation may be set into operation previous to the automatic brake valve handle assuming either of its brake 100 positions.

8. In combination with an automatic brake valve having a handle which may be brought to release and brake positions, a second handle adapted to be operated by the hand of an operator upon the handle of the automatic brake valve to cause a rail sanding operation previous to the brake valve handle assuming any of its brake positions, and said second handle returned to its non-operative 110 position by the valve handle when said valve handle assumes its release position.

9. In combination with an automatic brake valve of the character described, a rail sanding control valve normally detained from operation by the handle of the brake valve when the latter is set to released position and adapted to be operated when the said handle is moved from the released position of said brake valve, said control valve being rendered inoperative when said handle is moved past the service position of said brake valve.

10. In combination with an automatic brake valve of the character described, a rail 130

sanding control valve normally detained from operation by the handle of the brake valve when the latter is set to released position and adapted to be operated when the
5 said handle is moved from the released position of said brake valve, said control valve being rendered inoperative when said handle

is moved past the service position of said brake valve, and returned to normally inoperative position by said handle when the
10 latter is returned to the released position of said brake valve.

WILLIAM R. HOWDON.
